UNITED STATES PATENT OFFICE

MERVIN C. HUFFMAN, OF CLAREMONT, NEW HAMPSHIRE, ASSIGNOR TO SULLIVAN MACHINERY COMPANY, A CORPORATION OF MASSACHUSETTS

PRESSURE FLUID MOTOR

Application filed July 5, 1929. Serial No. 376,038.

This invention relates to pressure fluid motors and more particularly to pressure fluid motors of the impact type especially adapted to use in rock drills or similar types 5 of impact tools.

An object of this invention is to provide an improved pressure fluid motor. Another object is to provide an improved pressure fluid motor having improved fluid controlling and 10 distribution means. A further object is to provide an improved pressure fluid motor having an improved automatic distributing valve for controlling the motor fluid supply and exhaust and having improved actuating 15 means whereby the valve is shifted in one position by fluctuating pressures within the motor cylinder and in an opposite position by compression built up in the motor cylinder by the motor piston. Another object is to 20 provide an improved controlling valve and fluid distribution means for a pressure fluid motor of the impact type. These and other objects of this invention will, however, hereinafter more fully appear in the course of the 25 following description and as more particularly pointed out in the appended claims.

In the accompanying drawing there is shown for purposes of illustration one embodiment which the invention may assume 30 in practice.

In this drawing,—

Fig. 1 is a somewhat diagrammatic view illustrating one illustrative embodiment of the improved pressure fluid motor.

Fig. 2 is a view similar to Fig. 1, showing the parts in a different position.

In this illustrative embodiment of the invention there is shown a pressure fluid motor of the impact type, such as is commonly used 40 in rock drills or similar types of impact tools, comprising a motor cylinder 1 having a bore 2 in which a hammer piston 3 is reciprocably mounted. As is usual in motors of the type disclosed, the hammer piston 3 is provided 45 with a forward extension 4 of a reduced diameter fitting a bore 5 in the front head of the motor and this extension is herein in the form of a striking bar which is adapted to deliver repeated blows on the shank of a 50 usual drill steel or similar tool.

Now referring more particularly to the improved fluid controlling and distribution means, it will be noted that formed in a lateral projection or boss 6, herein preferably formed integral with the motor cylinder, is a 55 valve chamber having aligned differential bores 7 and 8 in which an automatic fluid distribution valve 9 is reciprocably mounted. This valve is herein of the two-spool differential type having spools 10 and 11 of the same 60 diameter fitting the bore 8 and connected by an intermediate reduced portion 12. As illustrated, the rearward end of the valve is provided with an enlarged radial flange 13 of a 65 diameter fitting the bore 7. Formed centrally within the valve 9, throughout a substantial portion of its length, is a bore 14 closed at its forward end by a transverse wall 15 forming the forward end surface of the valve. Fitting this bore 14 is a cylindrical projection 16, herein formed integral with a valve plug 17 suitably fixed within a bore 18 between the 70 rear motor head and the motor cylinder and having a cylindrical portion 19 fitting the bore 7, as clearly shown in the drawing. This 75 member has formed therein a chamber 20 vented through lateral slots 23 formed in the end of the valve buffer and a passage 24 to the atmosphere. A passage 25, extending through the projection 16, connects the bore 80 14 within the valve with the vented chamber 20 within the valve buffer. The forward end of the projection 16 limits movement of the valve in the rearward direction, while forward movement of the valve is limited by a 85 projection 26 against which the end wall 15 of the valve is adapted to abut. In order to reduce the weight of the valve to a minimum the forward end surface is grooved annularly at 27.

In this instance the motive fluid supply passage 28 extends longitudinally along one side of the valve and communicates with the bore 7 adjacent the forward end thereof by a lateral port 29 communicating with an enlarged 90 annular groove 30. A passage 31 connects the rear end of the bore 7 with the rear end of the cylinder bore 2, while a similar passage 32 communicates with the front end of the cylinder bore through a port 33 and connects 95 100

the front end of the cylinder with an enlarged annular groove 34 formed at the rear end of the bore 8. An exhaust passage 35 communicates with the bore 8 between the groove 34 and the forward end of the bore 8. Communicating with the cylinder bore substantially midway between its ends is a throwing passage 36 connecting the cylinder bore with the bore 8 at the forward end of the valve. 10 A free exhaust passage 37, controlled by the piston 3, is provided for relieving the pressure at each end of the piston stroke.

The operation of the improved pressure fluid motor is as follows. When the parts 15 are in the position shown in Fig. 1, live motive fluid flows through passage 28, through the port 29, through the groove 30 at the front end of the bore 7, past the rear surface of the valve through the bore 7 and through 20 passage 31 to the rear end of the cylinder bore 2. Simultaneously the forward end of the cylinder bore is connected to exhaust through port 33, passage 32, groove 34, through the valve chamber past the reduced 25 portion on the valve and through exhaust passage 35 to atmosphere. As a result, the pressure fluid flowing to the rear end of the cylinder bore acts on the rear piston area, thereby causing the piston to be driven forwardly to effect its working stroke. As the piston 3 moves forwardly, the passage 36 is 30 uncovered by the rear end of the piston and pressure fluid then flows from the rear end of the cylinder bore through this passage to the bore 8 at the forward end of the valve. 35 As the forward area of the valve is materially larger than the rear valve area surrounding the projection 16, and as the forward end surface of the bore 14 in the valve is vented 40 to atmosphere, the valve is thrown rearwardly from the position shown in Fig. 1 to the position shown in Fig. 2. The forward pressure area on the valve is then vented to atmosphere through passage 35 and the pressure 45 acting on the forward pressure area of the flange 13 holds the valve in this position. When the piston reaches the forward end of its working stroke, the free exhaust passage 37 is uncovered by the rear end of the piston, 50 thereby opening the rear end of the cylinder directly to atmosphere. When the valve is in the position shown in Fig. 2, live motive fluid flows from the passage 28, through port 29 and annular groove 30 past the reduced 55 portion 12 on the valve between the end spools, through annular groove 34, passage 32, and port 33 to the forward end of the cylinder bore. The pressure flowing through the front end of the cylinder acts on the forward piston 60 area, thereby driving the piston rearwardly to effect its return stroke. Continued rearward movement of the piston causes the fluid trapped within the rear end of the cylinder bore to be highly compressed and this compressed 65 fluid passes through passage 31 to the

bore 7 at the rear end of the valve. This relatively high compression pressure acts on the rear pressure area of the valve and causes the latter to be shifted from the position shown in Fig. 2 again to the position shown in Fig. 1, the pressure at the forward end of the valve being relieved at that time as mentioned above. When the piston nears the end of its rearward stroke the free exhaust passage is uncovered, thereby opening the front end of the cylinder bore to exhaust. When the valve is again in the position shown in Fig. 1, live fluid is admitted to the rear end of the cylinder bore while the forward end of the cylinder bore is exhausted to atmosphere and the sequence of events described above is repeated, thereby causing the hammer piston to be rapidly reciprocated within the cylinder as long as pressure fluid is supplied to passage 28.

As a result of this invention it will be noted that an improved pressure fluid motor is provided having an automatic fluid distribution of an extremely simple design and improved and simplified fluid distribution means, resulting in a motor having increased efficiency and at the same time materially reducing the cost of construction. It will further be noted that an improved pressure fluid motor is provided having an improved automatic fluid distributing valve which is thrown into one position by fluctuating pressures within one end of the cylinder and into its other position by compression built up in the motor cylinder by the motor piston. These and other advantages of this invention will, however, be clearly apparent to those skilled in this art.

While there is in this application specifically described one embodiment which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. A pressure fluid motor comprising a cylinder, a piston reciprocable in said cylinder, and fluid distribution means for effecting reciprocation of said piston including means forming a valve chamber having differential bores, a supply passage communicating with the larger of said bores, a passage leading from the larger bore to the rear end of said cylinder, a passage leading from the smaller of said bores to the front end of said cylinder, an exhaust passage connecting the smaller bore to atmosphere, a differential spool valve reciprocably mounted in said chamber for alternately connecting said second and third mentioned passages with said supply passage and for intermittently con-

neeting said third mentioned passage with said exhaust passage, means for subjecting the forward pressure area on said valve intermittently to the pressure in said cylinder, and 5 means for intermittently subjecting the opposed rear pressure area on said valve to compression built up in the rear end of the cylinder by said piston, said valve chamber forming means and said valve having portions co- 10 operating to make the said opposed rear pressure area on the valve of less area than the forward pressure area on said valve.

2. A pressure fluid motor comprising a cylinder, a piston reciprocable in said cylinder, and fluid distribution means for effecting reciprocation of said piston including a valve chamber having differential bores, a supply passage communicating with the larger of said bores, a passage leading from the 15 larger bore to the rear end of said cylinder, a passage leading from the smaller of said bores to the front end of said cylinder, an exhaust passage connecting the smaller bore to atmosphere, a differential valve having 20 spools fitting the smaller bore, one of the spools of said valve having an enlarged flanged portion fitting the larger bore, means for subjecting the forward pressure area on 25 said valve intermittently to the pressure in said cylinder, and means for intermittently subjecting the opposed rear pressure area on 30 said valve to compression built up in the rear end of the cylinder by said piston, said rear pressure area being of less extent than said 35 forward pressure area.

3. A pressure fluid motor comprising a cylinder, a piston reciprocable in said cylinder, and fluid distribution means for effecting reciprocation of said piston including a valve chamber having differential bores, a supply passage communicating with the larger of said bores, a passage leading from the larger bore to the rear end of said cylinder, a passage leading from the smaller of said bores to the front end of said cylinder, an exhaust passage connecting the smaller bore to atmosphere, a differential valve having spools fitting the smaller bore, one of the spools of said valve having an enlarged flanged portion fitting the larger bore, said valve having a forward pressure area and a smaller opposed rear pressure area, means for subjecting the forward pressure area on said valve intermittently to the pressure in said cylinder, means for intermittently subjecting the opposed rear pressure area on said valve to compression built up in the rear end of the cylinder by said piston, and means for subjecting the forward pressure area on said flange to the pressure in said supply passage to hold said valve in one position.

4. A pressure fluid motor comprising a cylinder, a piston reciprocable in said cylinder, and fluid distribution means for effecting reciprocation of said piston including means

forming a valve chamber having differential
holes, a supply passage communicating with
the larger of said bores, a passage leading
from the larger bore to the rear end of said
cylinder, a passage leading from the smaller
of said bores to the front end of said cyl- 70
inder, an exhaust passage connecting the
smaller bore to atmosphere, a differential
spool valve reciprocably mounted in said
chamber for alternatively connecting said
second and third mentioned passages with
said supply passage and for intermittently
connecting said third mentioned passage
with said exhaust passage, said valve having
a central bore extending only partially 75
through the same from the rear thereof, a
projection on said valve chamber forming
means fitting said bore, means for venting
said valve bore to atmosphere, means for
subjecting the forward pressure area on said
valve intermittently to the pressure in said 80
cylinder, and means for intermittently sub-
jecting the opposed rear pressure area on said
valve to compression built up in the rear end
of the cylinder by said piston. 85
90

5. A pressure fluid motor comprising a cylinder, a piston reciprocable in said cylinder, and fluid distribution means for effecting reciprocation of said piston including means forming a valve chamber having differential bores, a supply passage communicating with the larger of said bores, a passage leading from the larger bore to the rear end of said cylinder, a passage leading from the smaller of said bores to the front end of said cylinder, an exhaust passage connecting the smaller bore to atmosphere, a differential valve having spools fitting the smaller bore, one of the spools of said valve having an enlarged flanged portion fitting the larger bore, said valve having a central bore extending only partially through the same from the rear thereof, a projection on said valve chamber forming means fitting said bore, means for venting said valve bore to atmosphere means for subjecting the forward pressure area on said valve intermittently to the pressure in said cylinder, and means for intermittently subjecting the opposed rear pressure area on said valve to compression built up in the rear end of the cylinder by said piston. 95 100 105 110 115

6. A pressure fluid motor comprising a cylinder, a piston reciprocable in said cylinder, and fluid distribution means for effecting reciprocation of said piston including means forming a valve chamber having differential bores, a supply passage communicating with the larger of said bores, a passage leading from the larger bore to the rear end of said cylinder, a passage leading from the smaller of said bores to the front end of said cylinder, an exhaust passage connecting the smaller bore to atmosphere, a differential valve having spools fitting the smaller bore, one of the 123

spools of said valve having an enlarged flanged portion fitting the larger bore, said valve having a central bore extending only partially through the same from the rear thereof, a projection on said valve chamber forming means fitting said bore, means for venting said valve bore to atmosphere, means for intermittently subjecting the forward pressure area on said valve to the pressure in said cylinder, means for intermittently subjecting the opposed rear pressure area on said valve to compression built up in the rear end of the cylinder by said piston, and means for subjecting the forward pressure area on said flange to the pressure in said supply passage to hold said valve in one position.

7. A pressure fluid motor comprising a cylinder, a piston reciprocable in said cylinder, and fluid distribution means for effecting reciprocation of said piston comprising a reciprocable fluid distribution valve having a spool arranged to control admission of fluid to both ends of the cylinder and a second spool for controlling the exhaust from one end of the cylinder, said first mentioned spool having an enlarged flange providing a forward pressure area to hold the valve in one position, a piston controlled passage for subjecting said second spool to pressure for throwing said valve to one position, and means for subjecting the other spool to compression built up in the cylinder by said piston for throwing said valve to its other position, said last mentioned spool having an area subjected to compression smaller than the area on said second spool subjected to the pressure for throwing the valve.

8. A pressure fluid motor comprising a cylinder, a piston reciprocable in said cylinder, and fluid distribution means for effecting reciprocation of said piston comprising a differential fluid distributing valve for controlling the fluid distribution for said cylinder and having opposed pressure areas of different diameters, the area of larger diameter being of smaller extent, means for subjecting the forward pressure area of said valve to pressure within the cylinder, and means for subjecting said opposed area to compression built up in the rear end of said cylinder.

9. A pressure fluid motor comprising a cylinder, a piston reciprocable in said cylinder, and fluid distribution means for effecting reciprocation of said piston comprising a differential fluid distributing valve for controlling the fluid distribution for said cylinder and having opposed pressure areas of different diameters, the area of larger diameter being of smaller extent, means for subjecting the forward pressure area of said valve to fluctuating pressure within the cylinder, means for subjecting said opposed area to compression built up in the rear end of the cylinder, and another pressure area on

said valve adapted to be subjected to intermittent pressure acting in the same direction as the cylinder pressure for holding said valve in one position.

10. A pressure fluid motor comprising a cylinder, a piston reciprocable in said cylinder, and fluid distribution means for effecting reciprocation of said piston comprising a differential fluid distributing valve for controlling the fluid distribution for said cylinder and having opposed pressure areas of different diameters, the area of larger diameter being of smaller extent, means for subjecting the forward pressure area of said valve to pressure within the cylinder including a piston-controlled throwing passage connecting the cylinder with the forward end of said valve, and means for subjecting said opposed area to compression built up in the rear end of the cylinder.

11. A pressure fluid motor comprising a cylinder, a piston reciprocable in said cylinder, and fluid distribution means for effecting reciprocation of said piston comprising a differential fluid distributing valve for controlling the fluid distribution for said cylinder and having opposed pressure areas of different diameters, the area of larger diameter being of smaller extent, means for subjecting the forward pressure area of said valve to pressure within the cylinder including a piston-controlled throwing passage connecting the cylinder with the forward end of said valve, means for subjecting said opposed area to compression built up in the rear end of the cylinder, and another pressure area on said valve adapted to be subjected to intermittent pressure acting in the same direction as the cylinder pressure acting on the forward pressure area for holding said valve in one position.

12. In a pressure fluid motor, a cylinder, a piston reciprocable in said cylinder, and fluid distribution means for effecting reciprocation of said piston including means forming a valve chamber having small and large bores, a fluid supply passage communicating with the forward end of said large bore, a passage connecting the rear end of the large bore with the rear end of the motor cylinder, a passage communicating with said smaller bore intermediate its ends and leading to the front end of the cylinder, an exhaust passage communicating with the small bore between said third mentioned passage and the forward end of the small bore, an automatic fluid distribution valve reciprocable in the valve chamber and having spaced spools fitting the small bore and an enlarged rear flange fitting the large bore, means for subjecting the forward pressure area on said valve to throwing pressure to effect shifting of said valve into one position including a piston-controlled throwing passage connecting the small bore at the forward end of the

valve with the cylinder, and means for subjecting the opposed rear pressure area on said valve to compression built up in the rear end of the cylinder by said piston to shift said valve into its other position, said valve chamber forming means and said valve having portions cooperating to make the said opposed rear pressure area on the valve of less area than said forward pressure area on said valve.

13. In a pressure fluid motor, a cylinder, a piston reciprocable in said cylinder, and fluid distribution means for effecting reciprocation of said piston including means forming a valve chamber having small and large bores, a fluid supply passage communicating with the forward end of said large bore, a passage connecting the rear end of the large bore with the rear end of the motor cylinder, a passage communicating with said smaller bore intermediate its ends and leading to the front end of the cylinder, an exhaust passage communicating with the small bore between said third mentioned passage and the forward end of the small bore, an automatic fluid distribution valve reciprocable in the valve chamber and having spaced spools fitting the small bore and an enlarged rear flange fitting the large bore, means for subjecting the forward pressure area on said valve to throwing pressure to effect shifting of said valve into one position including a piston-controlled throwing passage connecting the small bore at the forward end of the valve with the cylinder, means for subjecting the opposed rear pressure area on said valve to compression built up in the rear end of the cylinder by said piston to shift said valve into its other position, and means for subjecting the forward pressure area on said valve to live pressure to hold said valve in one position, said valve chamber forming means and said valve having portions cooperating to make the said opposed rear pressure area on the valve of less area than said forward pressure area on said valve.

14. In a pressure fluid motor, a cylinder, a piston reciprocable in said cylinder, and fluid distribution means for effecting reciprocation of said piston including a valve chamber having small and large bores, a fluid supply passage communicating with the forward end of said large bore, a passage connecting the rear end of the large bore with the rear end of the motor cylinder, a passage communicating with said smaller bore intermediate its ends and leading to the front end of the cylinder, an exhaust passage communicating with the small bore between said third mentioned passage and the forward end of the small bore, an automatic fluid distribution valve reciprocable in the valve chamber and having spaced spools fitting the small bore and an enlarged rear flange fitting the large bore, means for subjecting the forward pressure area on said valve to live pressure to hold said valve in one position, said valve chamber forming means and said valve having portions cooperating to make the said opposed rear pressure area on the valve of less area than said forward pressure area on said valve.

ward pressure area on said valve to throwing pressure to effect shifting of said valve into one position including a piston-controlled throwing passage connecting the small bore at the forward end of the valve with the cylinder, means for subjecting the opposed rear pressure area on said valve to compression built up in the rear end of the cylinder by said piston to shift said valve into its other position, and means for venting a portion of the opposed rear pressure area on said valve to atmosphere.

15. In a pressure fluid motor, a cylinder, a piston reciprocable in said cylinder, and fluid distribution means for effecting reciprocation of said piston including a valve chamber having small and large bores, a fluid supply passage communicating with the forward end of said large bore, a passage connecting the rear end of the large bore with the rear end of the motor cylinder, a passage communicating with said smaller bore intermediate its ends and leading to the front end of the cylinder, an exhaust passage communicating with the small bore between said third mentioned passage and the forward end of the small bore, an automatic fluid distribution valve reciprocable in the valve chamber and having spaced spools fitting the small bore and an enlarged rear flange fitting the large bore, means for subjecting the forward pressure area on said valve to throwing pressure to effect shifting of said valve into one position including a piston-controlled throwing passage connecting the small bore at the forward end of the valve with the cylinder, means for subjecting the opposed rear pressure area on said valve to compression built up in the rear end of the cylinder by said piston to shift said valve into its other position, means for subjecting the forward pressure area on said valve to live pressure to hold said valve in one position, and means for venting a portion of the opposed rear pressure area on said valve to atmosphere.

16. A pressure fluid motor including a cylinder, a piston reciprocable in the cylinder, and fluid distribution means for effecting reciprocation of said piston including means forming a valve chamber having a plurality of bores of different sizes, a valve reciprocable in said valve chamber and having portions cooperating with said different bores, means for conducting live pressure fluid to said valve chamber, means for connecting longitudinally spaced portions of said valve chamber with an end of the cylinder and an intermediate point in the latter, and a valve having a forwardly facing surface on which line pressure acts continuously, a larger opposed surface on which line pressure acts during admission of the above mentioned end of the cylinder to effect strokes of said piston in one direction, and a still larger surface facing similarly to the first mentioned surface to

which pressure is admitted when said piston reaches in said strokes said intermediate point in the cylinder.

17. A pressure fluid motor including a cylinder, a piston reciprocable in the cylinder, and fluid distribution means for effecting reciprocation of said piston including means forming a valve chamber having a plurality of bores of different sizes, a valve reciprocable in said valve chamber and having portions cooperating with said different bores, means for conducting live pressure fluid to said valve chamber, means for connecting the valve chamber to opposite ends of the cylinder and to a point intermediate the ends of the cylinder, and means for connecting the valve chamber to atmosphere, said valve having a forwardly facing surface on which live pressure acts continuously, a larger opposed surface on which live pressure acts at the beginning and during a portion of each stroke of the piston in one direction, and a still larger surface facing similarly to the first surface to which pressure is admitted adjacent the end of such strokes.

In testimony whereof I affix my signature.

CERTIFICATE OF CORRECTION.

Patent No. 1,874,190.

August 30, 1932.

MERVIN C. HUFFMAN.

It is hereby certified that error appears in the printed specification of the above numbered patent requiring correction as follows: Page 3, line 110, claim 5, after "atmosphere" insert a comma; page 4, line 62, claim 9, for "pressure" read pressures; and page 5, line 127, claim 16, for "of" first occurrence read to; and that the said Letters Patent should be read with these corrections therein that the same may conform to the record of the case in the Patent Office.

Signed and sealed this 30th day of October, A. D. 1934.

Leslie Frazer

Acting Commissioner of Patents.
